UNITED STATES PATENT OFFICE

128,257

DESIGN FOR A FEED BOX FOR LATHES

William F. Groene and Harry C. Kemper, Cincinnati, Ohio, assignors to The R. K. Le Blond Machine Tool Company, Cincinnati, Ohio, a corporation of Delaware

Application March 24, 1941, Serial No. 99,822

Term of patent 14 years

To all whom it may concern:

Be it known that we, William F. Groene and Harry C. Kemper, citizens of the United States and residents of Cincinnati, county of Hamilton, and State of Ohio, have invented a new, original, and ornamental Design for a Feed Box for Lathes, of which the following is a specification, reference being had to the accompanying drawings, forming part thereof.

Figure I is a front elevational view of a feed box for lathes embodying our new design.

Figure II is a left hand end elevation of the feed box shown in Figure I.

Figure III is a right hand end elevation of the feed box shown in Figure I.

Figure IV is a plan view of the feed box shown in Figure I.

We claim:

The ornamental design for a feed box for lathes, substantially as shown.

WILLIAM F. GROENE.
HARRY C. KEMPER.
